Des. 1436

James McDuff, of Morrisania, N.Y.

Assignor to

A. Mc Graw and W. A. Taylor, of same place.
Letters Patent, No. 71, dated June 25, 1861,

Whole No. 1436.

The schedule referred to in these Letters Patent and making part of the same.

To all whom it may concern:

Be it known that I, James McDuff, of Morrisania, in the County of Westchester and State of New York, have invented or produced a new and original design for a Coffin, and I do hereby declare that the following is a full, clear and exact description thereof, reference being had to the accompanying drawings making a part of this specification, in which-

Figure 1, shows the top of the Coffin.

Figure 2, is an end view of the head of ditto.

Figure 3, is an end view of the foot of the Coffin.

Similar letters of reference indicate corresponding parts in the three figures.

This invention relates to a new and ornamental design for the cover or top, and the ends of a coffin, which I will proceed to describe.

The cover or top A, if seen in cross section taken through any point from the head, shoulder or foot is of a double ogee or raised serpentine shape, and this cover is suitably pitched or inclined from the shoulder a. to the ends thereof. The edges of cover A, both at the ends and sides, may be rounded as shown in figures 2 and 3, or any ornamental head may be formed thereon. The central part or elevated portion of the top A, should be well arched leaving the surfaces on each side of this central part, or ridge, gently curved inwards, as represented in figures 2 and 3, of the drawings.

The ends of the coffin, that is to say, the head B and foot C, have the same double or right and left ogee shape as the top A, as represented in figures 2 and 3, of the drawings, and the top edges of the head and foot portions B and C, should be curved correspondingly to their respective ends of the top A.

The sides C, C, and the bottom D, of the coffin are flat as in common coffins.

Having thus described my design for a Coffin, what I claim as new and desire to secure by Letters Patent, is -

The double ogee or serpentine raised top A, and ends B, C, corresponding in configuration with the top as herein described and represented.

Witnessed,

Bilas D. Gifford. }
Augustus P. McGuire. }

550 James McDuff.
